UNITED STATES PATENT OFFICE.

WILLIAM W. LASKER, OF BROOKLYN, NEW YORK, ASSIGNEE, BY MESNE ASSIGNMENTS, TO POWERS ACCOUNTING MACHINE CORPORATION, OF NEW YORK, N. Y., A CORPORATION OF DELAWARE.

CIPHER CUT-OUT MECHANISM.

Application filed December 24, 1917. Serial No. 208,566.

To all whom it may concern:

Be it known that I, WILLIAM W. LASKER, a citizen of the United States, residing in borough of Brooklyn, in the county of 5 Kings and State of New York, have invented certain new and useful Improvements in Cipher Cut-out Mechanisms, of which the following is a specification.

This invention relates to printing 10 counting machines and has for its object to provide zero cut-out mechanisms for preventing the printing of zeros before the numerical digit of the highest decimal order of a number.

15 My invention is shown applied to an accounting machine having registering and printing elements comprising type segments. Such a machine is fully described in my copending application, Serial No. 158,142, filed March 28, 1917; and, therefore, only 20 the parts of such machine are described as are necessary for an understanding of the new invention.

The new zero cut-out comprises zero supports pivoted to each of the type segments and each provided with a cam-engaged adjustable roller-carrying bracket which is instrumental in moving the zero support to printing position as will be explained.

30 Another object is to provide adjustable means for printing decimals or the like between the characters.

These and other objects will appear when the invention proceeds; and while herein I 35 have described minute details of the invention the invention is not limited to these, since the details of construction and combination may be greatly varied without departing from the spirit and scope of the invention as claimed.

In the accompanying drawing showing by way of example, one of many possible embodiments of my invention;—

Figure 1 is a fragmental side elevation of 45 a registering and printing element showing the type segment and the zero support of the next lower order both retracted from printing position;

Fig. 2 is a fragmental side elevation showing 50 a type segment with its zero support moved to printing position by the cam of the next higher order;

Fig. 2^a is a plan showing registering and printing elements in the position of Fig. 2;

Fig. 3 is a fragmental side elevation showing a type segment in retracted position and its roller bracket adjusted to inoperative position;

Fig. 4 is a similar view showing a type segment in zero position, the zero support 60 in non-printing position, and the roller bracket in inoperative position;

Fig. 4^a is a plan showing one element in the position of Fig. 4 and the remaining elements in the position of Fig. 2^a;

Fig. 5 is a fragmental perspective view showing the zero supports and the adjacent cooperating parts;

Fig. 6 is a side elevation of a cam roller bracket;

Fig. 7 is an edge view of the same;

Fig. 8 is a side elevation of a zero support;

Fig. 9 is an edge view of the latter;

Fig. 10 is a face view of a decimal plate 75 for printing decimals or separating lines between characters; and

Fig. 11 is a face view of a strip of paper showing matter printed by the new invention.

In the said copending application means are shown for feeding perforated cards to an analyzer comprising a reciprocating pin box provided with pins adapted to feel the cards and on finding perforations therein to 80 press therethrough to raise registering stops corresponding to perforations corresponding to numerals, the naught stops being normally raised and adapted by suitable connections to be depressed by the raising of a 90 numeral registering stop.

Referring more particularly to the drawing of the present specification, there are shown a plurality of numeral registering stops 10, (Fig. 1), of the kind just mentioned. These are arranged in rows and associated with each row is a naught stop 11 and a reciprocating rack bar 12 provided with a shoulder 14 adapted to engage the rear face of one of said stops 10 or 11 100 as the rack bar is brought forward by means of the transverse bar 15 which is reciprocated by suitable means as shown in said copending application.

This transverse bar 15 engages a drive 105 shoulder 16 on the pivoted bar 18 pivoted at its forward end to said rack bar 12 and yieldably held in raised position by a

spring 19 strained between its rear end and a bracket 20 on the rear of the rack bar.

said pivoted bar is lowered from normal position to the one shown in Fig. 1, by means 6 of a small lever 21 pivoted to the rack bar 12 and having pin and slot connections 22 with the pivoted bar 18. The lower end of said lever 21 engages whichever registering stop is raised as said shoulder 14 is stopped 19 thereby, in this manner lowering the pivoted bar 18 and shoulder 16 and releasing the transverse bar 15 to permit it to pass on after the rack bar has been set in accordance with said raised stop.

15 On its return, the transverse bar 15 engages the abutment 24 and restores the rack bar to normal position.

Meshing with each rack bar 18 is a pinion 30 secured to the side of a type segment 31 mounted on a shaft 32, and carrying a plurality of numeral type 34 and provided with gear teeth 25 adapted to engage with accumulator wheels not shown herein. The type segment 31 has a portion 70 having an inner edge 71 and an outer edge 72, the inner edge 71 being provided with a plurality of recesses 73 spaced from one another. The numeral type 34 have laterally extending lugs 74 and 75, the lugs 74 of which are 25 adapted to engage the recesses 73 while the lugs 75 engage the outer edge 72 of the portion 70. The numeral type being thus aligned, are then fastened in place by the rivets 76. The platen 35 brings the paper 30 against the type at the proper times.

The parts mentioned above are explained in detail in said copending application and need not be further described here.

Pivottally mounted upon each type segment 31 is a zero type-carrying support 38 (Fig. 9), mounted on the pivot pin 39 and normally held in non-printing position by means of a spring 40 strained between an eye 41 on the type segment and a tail 42 carried upon said zero carrying support. The zero carrying support is limited in its retractive movement by means of a lug 44 engaging against the edge of the type segment.

50 Pivoted upon said same pin 39 is a roller carrying bracket 46 (Fig. 6), provided with a pair of recesses 48 and 49 in either of which the zero type 50 carried on said support may be engaged. Each roller carrying bracket is provided with a short pin 51 adapted to be engaged by the pin engaging lug 52 of the roller carrying bracket of the next higher order. There is also carried on each bracket a cam engaging 55 roller 54 adapted to be engaged by a cam 55 secured to the type segment 31 of the next higher order. The metal of the roller carrying bracket and the zero carrying support is made slightly elastic and the zero type 60 may be removed from either recess 48

or 49 and placed in the other merely by slightly separating said bracket and support by means of any suitable pointed instrument such for instance as a pen-knife. When the zero type is placed in the recess 70 49, the roller 54 is held out of operative engagement with the cam 55. A small lug 68 carried on the bracket 46 limits its movement relative to the zero support.

Just before a card is analyzed the rack bars are in retracted position with the shoulder 14 a distance behind the naught stop. At this time the segments occupy the position of Fig. 1. When a card is analyzed, if there be no perforation representing numbers higher than zero, as in the first item of sheet 57 (Fig. 11), the numeral type take the position shown in Fig. 2, but a zero type positioned in the recess 48 will not be moved to the printing position 80 it occupies in Fig. 2 because no cam 55 will have moved far enough to engage the roller 54. If, however, the segments of the lower order and segments of a higher order be moved only to the zero position, and a segment of an intermediate order be moved to print a numeral greater than zero, as in the second item of Fig. 11, the cam 55 of such intermediate segment will engage the roller 54 of the zero positioned segment of the next lower order and draw the associated zero support 38 down to zero-printing position as shown in Fig. 2. The lug 52 of the support thus drawn down will engage the pin 51 of the roller bracket to its left. 85 of the next lower order, which will in turn bring down the next zero support, and so on until the end of the series of zero positioned type segments, unless some one of the roller brackets has been adjusted to inoperative position as will be further explained.

On the other hand, however, the zero supports 38 of the zero positioned segments of an order higher than said intermediate segment, will not be brought down because the cam 55 of a segment engages the roller of the next lower order and not of a higher order; and nothing will be printed by the zero-positioned segments of the orders higher than said intermediate segment.

If there be several immediately adjacent zero-positioned intermediate segments between numeral-positioned segments of higher order and of lower order, as in the third row of Fig. 11, the cam 55 of a higher order segment will bring down the zero-support of the nearest of said intermediate segments and the lug 52 of such zero-support will bring down the next lower zero support and so on for all of said immediately adjacent zero positioned segments until said numeral positioned lower order segments have been reached. Of these latter, the zero supports have, of course, moved

out of reach of the lug 52 of the zero support of the zero-positioned type segments.

Should it be desired to break the operative connection between any zero support and the element of the next higher order, the roller carrying bracket 46 of such zero-support will be moved until its recess 49 receives the zero type 50, in which case the roller 54 and the pin 51 thereof will be disposed entirely out of the paths of the cam 55 and the lug 52 of the segment of the next higher order, as shown in Figs. 4 and 4^a, thus, as it were, dividing the printing element into zones, in which case two items such as in the last three rows of Fig. 11 could be printed.

In view of the above, it is obvious that any numeral positioned type segment of any zone will cause the drawing down, to zero printing position, of all of the zero type supports of all of the successively adjacent zero positioned type segments of that same zone; and that no numeral positioned type segment will effect the drawing down of a zero type support of a higher order.

If it be desired to print a decimal or other mark 58 of separation between adjacent columns of the printed sheet 57, this is done by means of the printing points 59, (Fig. 10), of the decimal or separating plate 60, which plate may be secured to segment 38 by screws 61, (Fig. 3). One or more of these plates may be placed wherever thought desirable, or omitted entirely.

35 I claim as my invention:

1. In a machine of the character described, the combination of a plurality of numeral type carriers; and a zero type carrying support carried entirely on each carrier and adapted to be modified to assume a normal or abnormal condition, and being, when in said abnormal condition, free from any influence by the carrier of the next higher order, and adapted, when in said normal condition, to be moved to printing position by a carrier of the next higher order.

2. In a machine of the character described, the combination of a plurality of type carriers each provided with a series of numeral type; and a zero type carrying support mounted on each carrier in non-printing position and adapted to be at will modified to assume a normal or abnormal condition, and being, when in said abnormal condition, free from any influence by the carrier of the next higher order, and adapted, when in said normal condition, to be moved to printing position by a numeral positioned carrier of the next higher order.

3. In a machine of the character described; the combination of a plurality of type carriers each provided with a series of numeral type; and a zero type carrying support mounted on each carrier in non-

printing position and adapted to be at will modified to assume a normal or abnormal condition, and being, when in said abnormal condition, free from any influence by the carrier or zero type carrying support of the next higher order, and adapted, when in said normal condition, to be moved to printing position by a zero positioned zero type carrying support or a numeral positioned type carrier of the next higher order.

4. In a machine of the character described, the combination of a plurality of numeral type carriers; a zero type carrying support associated with each carrier and adapted to be caused to assume a normal or abnormal condition, and adapted, when in said normal condition, to be by a zero type carrying support influenced to assume an operative condition, and when in abnormal position to be free from such influence.

5. In a machine of the character described, the combination of a plurality of numeral type carriers; and a zero type carrying support associated with each carrier and adapted to be caused to assume a normal or abnormal condition, and adapted, when in said normal condition, to be influenced by an adjacent carrier to assume an operative condition, and when in said abnormal position to be free from such influence.

6. In a machine of the character described, the combination of a plurality of numeral type carriers; and a zero type carrying support associated with each carrier and adapted to be at will manipulated to assume a normal or abnormal condition, and adapted, when in said normal condition, to be influenced by an adjacent zero support or an adjacent carrier to assume an operative condition, and when in said abnormal position to be free from influence by the carrier of the next higher order in any position of said carrier.

7. In a machine of the character described, the combination of a plurality of type carriers; a zero type carrying support mounted on each carrier in non-printing relation thereto and comprising a pair of relatively movable parts adapted to be held in normal or abnormal relation relative to each other and being, when in said abnormal relation, outside of the path of the zero type carrying support of the next higher order, and adapted, when in said normal relation, to be moved to printing position by a zero positioned zero type support of the next higher order.

8. In a machine of the character described, the combination of a plurality of type carriers; a zero type carrying support mounted on each carrier in non-printing position; a bracket movably associated with each zero type carrying support and adapt-

ed to be held in normal or abnormal relation relative to the zero support, and being, when in said abnormal relation, outside of the path of the carrier or zero type carrying support of the next higher order, and adapted, when in said normal relation, to be moved, by a zero positioned zero type carrying support or a numeral positioned type carrier of the next higher order, to 10 printingly position its associated zero support.

9. In a machine of the character described, the combination of a plurality of type carriers each provided with a series of 15 numeral type and a cam; a zero type carrying support mounted on each carrier in non-printing position; a bracket movably associated with each zero type carrying support and adapted to be held in normal or 20 abnormal relation relative to the zero type carrying support, and being, when in said abnormal relation, outside of the path of the cam or zero type carrying support of the next higher order, and adapted, when 25 in said normal relation, to be moved, by a zero positioned zero support or a numeral positioned cam of the next higher order, to printingly position its associated zero type carrying support.

10. In a machine of the character described, the combination of a plurality of type carriers each provided with a series of 30 numeral type; a cam carried on each type carrier; means for printingly positioning the carriers; a zero type carrying support pivotally mounted on each carrier in non-printing position; a bracket pivotally mounted against each zero type carrying support and adapted to be held in normal or 35 abnormal relation relative to the zero type carrying support, and being, when in said abnormal relation, outside of the path of the cam or zero type carrying support of the next higher order, and adapted, when in said normal relation, to be moved, by a zero positioned zero type carrying support or a numeral positioned cam of the next higher order, to printingly 40 position its associated zero type carrying support.

11. In a machine of the character described, the combination of a plurality of type carriers each provided with a series of 45 numeral type and a cam; a zero type carrying support pivotally mounted, on each carrier, in non-printing position; a bracket pivotally mounted against each zero type carrying support and adapted to be held in normal or 50 abnormal relation relative to the zero type carrying support, and being, when in said abnormal relation, outside of the path of the cam or zero type carrying support of the next higher order, and adapted, when in said normal relation, to be moved, by a zero positioned zero support.

port or a numeral positioned cam of the next higher order, to printingly position its associated zero type carrying support.

12. In a machine of the character described, the combination of a plurality of 70 type carriers; a series of numeral type on each carrier; means for positioning the carriers; a zero type carrying support pivotally mounted on each carrier and yieldably held in non-printing position and provided 75 with a lug; and a bracket pivotally mounted against each support and provided with means for holding the bracket in normal or abnormal relation relative to said support, each bracket being, when in said abnormal 80 relation, outside of the path of said lug, and adapted, when in said normal relation, to be engaged by the lug of the support of the next higher order to hold such bracket and the associated support in printing position when said higher order support is in printing position.

13. In a machine of the character described, the combination of a plurality of 85 type carriers; a series of numeral type on each carrier; means for positioning the carriers; a cam carried on each carrier; a zero type carrying support mounted on each carrier and yieldably held in non-printing position; a bracket pivotally mounted adjacent to each support and provided with means for holding the bracket in normal or 90 abnormal relation relative to said support, each bracket being, when the bracket is in said abnormal relation outside of the 95 path of the cam of the carrier of the next higher order, and adapted, when in said normal relation, to be engaged by the said cam of the next higher order to move to zero printing position its associated support.

14. In a machine of the character described, the combination of a plurality of type carriers; a series of numeral type on each carrier; means for positioning the carriers; a cam carried on each carrier; a zero type carrying support pivotally mounted on each carrier and yieldably held in non-printing position; a bracket pivotally mounted adjacent to each support and provided with means for holding the bracket 110 in normal or abnormal relation relative to said support; and a roller on each bracket, said roller being, when the bracket is in said abnormal relation, outside of the path of the cam of the carrier of the next higher 115 order, and adapted when in said normal relation, to be engaged by the said cam of the next higher order to move to zero printing position its associated support.

15. In a machine of the character described, the combination of a plurality of type carriers; a series of numeral type on each carrier; means for positioning the carriers; a cam carried on each carrier; a zero type carrying support pivotally 120

- mounted on each carrier and yieldably held in non-printing position and provided with a lug; a roller-carrying-bracket pivotally mounted against each support and provided with means for holding the bracket in normal or abnormal relation relative to said support, each bracket being, when in said abnormal relation, outside of the path of said lug, and adapted when in said normal relation, to be engaged by the lug of the support of the next higher order to hold such bracket and the associated support in printing position when said higher order support is in printing position; and a roller on each roller-carrying-bracket, said roller being, when the bracket is in said abnormal relation, outside of the path of the cam of the carrier of the next higher order, and adapted when in said normal relation, to be engaged by the cam of the next higher order to move to zero printing position its associated support.
16. In a machine of the character described, the combination of a plurality of type carriers; a series of numeral type on each carrier; means for positioning the carriers; a zero type carrying support pivotally mounted on each carrier and yieldably held in non-printing position and provided with a lug; a roller-carrying-bracket pivotally mounted against each zero type support and provided with means for holding the bracket in normal or abnormal relation relative to said support, each bracket being provided with a pin adapted to be engaged by the lug of the support of the next higher order to hold such bracket and the associated support in printing position when said higher order support is in printing position; a roller on each roller-carrying-bracket; and a cam carrier on each type carrier and adapted, when such type segment is moved beyond zero position to engage the roller of the normally positioned bracket of the next lower order and move to zero printing position the support associated with such lower order bracket.
17. In a machine of the character described, the combination of a plurality of type segments; a series of numeral type on each segment; means for rotating the segments to printingly position selected type; a zero type carrying support pivotally mounted on each segment and yieldably held in non-printing position and provided with a lug; a roller-carrying-bracket pivotally mounted against each support and provided with means for holding the bracket in normal or abnormal relation relative to said support, each bracket being provided with a pin adapted to be engaged by the lug of the support of the next higher order to hold such bracket and the associated support in printing position when said higher order
- support is in printing position; a roller on each roller-carrying-bracket; and a cam carried on each type segment and adapted, when such type segment is moved beyond zero position to engage the roller of the normally positioned bracket of the next lower order and move to zero printing position the support associated with such lower order bracket.
18. A type bar for accounting machines and the like, comprising a relatively thin type carrier, means for supporting the same against printing strains, type of greater thickness than the carrier having a cut-away portion adapted to fit against the face of the carrier and a flat shoulder near the head of the type adapted to bear against the edge of the type carrier to transmit printing strains to the type carrier, and means for holding such shoulder in proper position against such edge.
19. A type bar for accounting machines and the like comprising a relatively thin type carrier, means for supporting the same against printing strains in spaced relation from other parts of the mechanism, type of greater thickness than such carrier having a cut-away portion equal in length to the effective width of the carrier, so arranged that a flat shoulder is formed near the head of the type adapted to press against an edge of the carrier to transmit printing strains to the carrier, and another shoulder is formed near the back end of the type adapted to contact with the other edge of the carrier to prevent longitudinal movement of the type in relation to the carrier and thereby to prevent the type from pivoting in relation to the carrier, means for holding the type against movement longitudinally of the carrier and means for holding the cut-away portion of the type against the face of carrier.
20. A structure as defined in claim 19, in which the means for holding the type against longitudinal movement of the carrier comprises notches formed on one edge of the carrier.
21. A structure as defined in claim 20, in which the notches are positioned to receive the shoulders on the type which are formed near the back of the type.
22. A structure as defined in claim 19 in which the cut-away portions of the type are held against the face of the carrier solely by attaching members which pass through the type and the carriers.
23. A structure as defined in claim 19 in which the type carrier is curved so that its edge forms an arc of a circle.
